CLAIM

The ornamental design for a toilet pedestal, as shown and described.

DESCRIPTION

FIG. 1 is a perspective view of the toilet pedestal, showing my new design;

FIG. 2 is a top elevation of the toilet pedestal;

FIG. 3 is a bottom elevation thereof;

FIG. 4 is a front elevation thereof; and,

FIG. 5 is a right side elevation of the toilet pedestal illustrated in FIGS. 1-4.

The broken line showing of the toilet is for illustrative purposes only and forms no part of the claimed design.
